R. D. McWane Attorney

UNITED STATES PATENT OFFICE.

ARTHUR T. MCWANE, OF BIRMINGHAM, ALABAMA.

WINDOW GUARD.

Application filed September 3, 1927. Serial No. 217,363.

My invention relates to window guards, more particularly to a window guard for the lower sash of the commonly used two-sash window, and has for its object the provision of a simple effective device of the character designated, which shall be easily and readily raised to open position and lowered to closed position, and which shall include means accessible only from the inside of the window for locking the guard in closed position.

Briefly, my invention consists of a guard for the lower part of a two-sash window, said guard having a frame and means to raise it clear of the lower window sash when the guard is not needed and to lower it to closed position, together with novel and effective means accessible only from the inside of the window for locking the guard and the upper window sash against intruders, said means being accessible from the inside only when the lower sash is closed. In my application for Letters Patent filed concurrently herewith, Serial No. 217,364, I have shown, described and claimed a telescoping window guard together with means for locking the guard and the upper sash of the window in closed position. In the window guard shown in this application, I employ similar locking means, but design the guard with a rigid frame, and provide novel means for mounting and operating the guard. A device embodying features of my invention is illustrated in the accompanying drawing, forming a part of this application, wherein

Fig. 1 is a front elevation of a window having my improved guard applied thereto;

Fig. 2 is a sectional view taken along the line II—II of Fig. 1;

Fig. 3 is a view in elevation of the guide means and operating mechanism of my improved window guard removed from the window frame, and showing a fragment of the guard in section; and

Fig. 4 is a fragmentary sectional view taken along the line IV—IV of Fig. 2.

Referring now to the drawing for a better understanding of my invention, I show a window frame 10 provided with upper and lower sash 11 and 12, respectively. Secured to the side of the frame 10 are guide rails 13, 14 and 16, which cooperate to form spaced-apart guides for the upper and lower sash. As is well understood, the upper sash

and its guides are arranged forwardly of the lower sash and its guides. In this specification the terms "front" and "rear," and their derivatives, are used to designate parts toward the outside and toward the inside, respectively, of the room in which the window is located. The upper sash 11 has a relatively wide lower rail 17 provided with a beveled side adapted to extend under a similarly formed upper rail 18 of the lower sash 12 to effectively close the window against cold air, moisture, etc., when desired. Both the rail 17 and the rail 18 are provided with notched ends, as shown at 21 in Fig. 4, in order to freely slide over the guide rail 14 and the guide means for my improved window guard, which will presently be described.

My improved window guard comprises a frame 22 having secured thereto suitable guard means 23. The guard means is shown in the drawing as comprised of wire mesh, but it is to be understood that any suitable guard means may be employed. The frame 22 is disposed forwardly of both of the window sash and slides in a pair of vertically disposed guides 24 secured to the window frame 10 as by screws 25, shown in dotted lines in Fig. 3, so as to be covered by the guide frame 22 when the window guard is closed. Secured to the lower edge of the frame 22 is a rearwardly and upwardly extending member 26, the upwardly extending portion thereof fitting into guides 27. The guides 27 are secured to the guide rails 14 interposed between the guide rails 13 and 16. The guides 27 are secured by screws 30 which are so positioned as to be covered by the upwardly extending member 26 when the guard is closed. The guide 27 is formed from a square tube having a slit 28 in its side to permit the upwardly extending portion of the member 26 to be raised with the window guard. The latter upwardly extending portion of the member 26 is made larger than the slit 28 so that it is prevented from slipping forwardly out of the guide.

Secured to the upper end of the member 26 is a pivoted latch 31 adapted to be turned to the position shown in Fig. 4 where it engages with a notch 32 formed on the rear side of the lower part of the upper sash 11 and with a notch 33 formed in the side of the guide 27. When thus turned, the guard is down in closed position and the

upper sash 11 is up in closed position and the two are securely held so that neither can be opened except when the latch 31 is released from the inside of the window. Furthermore, should the latch 31 be turned so as to be disengaged from the notch 32, the guard could not be raised until turned around sufficiently to clear the notch 35. Whenever it is desired to raise the guard 23, the latch 31 is turned around to the dotted position shown in Fig. 4 where it overhangs the upper rail 18 of the lower sash 12, whereupon the guard may be raised to open position by raising the lower sash 12. The upper side of the guard frame 22 is provided with a latch 36 which is adapted, when the guard is raised to open position, to be engaged by a latch 37, which yieldingly holds it in its raised, open position. Whenever it is desired to lower the guard to its closed position, the members 26 may be grasped from the inside of the window and pulled down to release the latch 37, whereupon the guard may be lowered.

From the foregoing, it will be apparent that I have devised a simple effective window guard which may be readily closed to keep out intruders, or opened when desired, and which, when closed, may be effectively locked by means accessible only from the inside of the window.

While I have shown my invention in but one form, it will be obvious that those skilled in the art that it is not so limited, but is susceptible of various changes and modifications, without departing from the spirit thereof, and I desire, therefore, that only such limitations shall be placed thereupon as are imposed by the prior art or as are specifically set forth in the appended claims.

What I claim is:

1. The combination with a window having a frame with upper and lower sash, and a guard for the lower sash arranged forward of both sash, of guard retaining means disposed to the rear of the upper sash and permitting raising and lowering of the guard, and means co-acting with said guard retaining means to lock the guard in closed position.
2. The combination with a window having a frame with upper and lower sash, and a guard for the lower sash arranged forward of both sash, of guard retaining means disposed to the rear of the upper sash and permitting raising and lowering of the guard, and means co-acting with said upper sash and said guard retaining means to lock the guard and the sash in closed position.
3. The combination with a window having a frame with upper and lower sash, and a guard for the lower sash arranged forward of both sash, of guard retaining means disposed to the rear of the upper sash and permitting raising and lowering of the guard,
4. The combination with a window having a frame with upper and lower sash, and a guard for the lower sash arranged forward of both sash, of guard retaining means disposed to the rear of the upper sash and permitting raising and lowering of the guard, and means accessible only from the inside of the window and co-acting with retaining means to lock the guard in closed position.

4. The combination with a window having a frame with upper and lower sash, and a guard for the lower sash arranged forward of both sash, of guard retaining means disposed to the rear of the upper sash and permitting raising and lowering of the guard, and means accessible only from the inside of the window and co-acting with retaining means to lock the guard in closed position.

4. The combination with a window having a frame with upper and lower sash, and a guard for the lower sash arranged forward of both sash, of guard retaining means disposed to the rear of the upper sash and permitting raising and lowering of the guard, and means accessible only from the inside of the window and co-acting with retaining means to lock the two in closed position.

5. The combination with a window having a frame with upper and lower sash and a guard for the lower sash arranged forward of both sash, of guard retaining means disposed intermediate the two sash and including a member slidably upward between the two sash permitting raising and lowering of the guard, and means co-acting between said member and the upper sash to latch the guard and the sash in closed position.

6. The combination with a window having a frame with upper and lower sash and a guard for the lower sash arranged forward of both sash, of guard retaining means disposed intermediate the two sash and including a member slidably upward between the two sash permitting raising and lowering of the guard, and a pivoted latch secured to the member and adapted to co-act with a stationary part of the retaining means to lock said guard in closed position, said latch also being adapted to be turned into operative relation with the lower sash to raise the guard to open position when the lower sash is raised.

7. The combination with a window having a frame with upper and lower sash and a guard for the lower sash arranged forward of both sash, of guard retaining means disposed intermediate the two sash and including a member slidably upward between the two sash permitting raising and lowering of the guard, and a pivoted latch secured to the member and adapted to co-act with a stationary part of the retaining means and the upper sash to lock said sash and said guard in closed position, said latch also being adapted to be turned into operative relation with the lower sash to raise the guard to open position when the lower sash is raised.

8. The combination with a window having a frame with upper and lower sash and a guard for the lower sash arranged forward of both sash, of guard retaining means disposed intermediate the two sash and including a member slidably upward between the two sash permitting raising and lowering of the guard, a pivoted latch secured to the member and adapted to co-act with the upper sash to lock said sash and said guard in closed position, said latch

also being adapted to co-act with the lower sash to raise the guard to open position when the lower sash is raised, and means for automatically engaging and holding the guard in raised position.

9. The combination with a window having a frame with upper and lower sash and a guard for the lower sash arranged in front of both sash, of a rigid frame for the guard, front and rear guides for the upper and lower sash, respectively, a vertically extending guide disposed to the rear of the front sash guide, a rearwardly projecting runner secured to the guard and fitting into the last mentioned guide, and latch means cooperating between the runner, the guide and the upper sash to hold said sash and runner with the guard and upper sash in closed position.
10. A device as claimed in claim 9 wherein the latch means may be turned to overhang the lower sash when said sash is down, whereby both the lower sash and the guard may be raised by raising the lower sash.

11. The combination with a window having upper and lower sash and a guard for the window, of a frame for the guard, guide means for the guard frame arranged near the outer edge of the window frame, spaced-apart guides for the upper and lower sash, respectively, guide means interposed between the spaced-apart guides, a runner secured to each side of the guard frame and extending rearwardly and upwardly to slidably fit in the guide means, and a latch secured to each runner and adapted to co-act with the guide means for locking the guard in closed position.

12. The combination with a window having upper and lower sash and a guard for the window, of a frame for the guard, guide means for the guard frame arranged near the outer edge of the window frame, spaced-apart guides for the upper and lower sash, respectively, guide means interposed between the spaced apart guides, a runner secured to each side of the guard frame and extending rearwardly and upwardly to slidably fit in the guide means and a latch ac-

cessible only from the inside of the window, secured to each runner and co-acting with the upper sash to retain the guard and the upper sash in closed position.

13. The combination with a window having upper and lower sash and a guard for the window, of a frame for the guard, guide means for the guard frame arranged near the outer edge of the window frame, spaced-apart guides for the upper and lower sash, respectively, guide means interposed between the spaced-apart guides, a runner secured to each side of the guard frame and extending rearwardly and upwardly to slidably fit in the guide means, and a latch accessible only from the inside of the window when the lower sash is closed, secured to each runner and co-acting with the upper sash to retain the guard and the upper sash in closed position, said latch being adapted, when desired, to engage the upper rail of the lower sash whereby the guard and the inner sash may be raised simultaneously.

14. The combination with a window having upper and lower sash and a guard for the window, of a frame for the guard, guide means for the guard frame arranged near the outer edge of the window frame, spaced-apart guides for the upper and lower sash, respectively, guide means interposed between the spaced-apart guides, a runner secured to each side of the guard frame and extending rearwardly and upwardly to slidably fit in the guide means, a latch accessible only from the inside of the window when the lower sash is closed, secured to each runner and co-acting with the upper sash to retain the guard and the upper sash in closed position, said latch being adapted, when desired, to engage the upper rail of the lower sash whereby the guard and the lower sash may be raised simultaneously, and means for automatically engaging the guard and holding it in raised position to permit lowering of the lower sash when desired without lowering the guard.

In testimony whereof I, ARTHUR T. McWANE, affix my signature.

ARTHUR T. McWANE.
